METHOD OF MAKING COLUMNS AND THE
LIKE

Clinton H. Sawyer, New York, N. Y.

Original application March 14, 1930, Serial No.
435,829. Divided and this application April 20,
1931. Serial No. 531,358

1 Claim. (Cl. 29—155)

This invention relates to the making of columns of straight, tapered, or entasis form, and it is the object of the invention to provide an improved method of reducing the size of tubes or 5 sections of arcuate shape in cross section to smaller size of either straight, tapered or entasis form for use as flag poles, masts, booms, spars and the like, the same being for subject-matter divided out from my application Serial No. 435,829, which 10 has matured in Letters Patent No. 1,871,743, issued August 16, 1932.

In carrying out the invention longitudinal portions of a tube of uniform diameter are removed to provide slots tapering from one end toward the 15 opposite end of the tube and then the portions of the tube between the slots are shaped to curved shape in cross section to extend through an arc of 180 degrees for the entire length of the tube and the opposite walls of the slots brought and 20 secured in abutting relation.

In the drawings accompanying and forming a part of this application Figure 1 is a cross sectional view, on an enlarged scale, taken on the line 1—1 of Figure 2 looking in the direction of 25 the arrows and at the end of the arrows and at the end of the die.

Figure 2 is a side elevation with a supporting sill removed to illustrate the operative parts.

Figures 3 and 4 are side and end elevations, respectively, of a die carrying head.

Figures 5 and 6 are front and side elevations, respectively, of an actuator for die adjusting means mounted on the die carrying head.

Figures 7 and 8 are side and end elevations, respectively, of a die member.

Figure 9 is a perspective view of a column or tube arranged preparatory to forming it to tapered entasis form by drawing or passing the tube through the die.

Figures 10 and 11 are end and side views showing the manner of making the tapering slots in a tube of uniform diameter preparatory to shaping a tube to tapered and entasis form.

Figure 12 is a perspective view of a tube with the section arranged with the portions between the tapering slots shaped to extend through an arc of 180 degrees and the opposed edges of said portions brought into abutting relation; and

Figure 13 is a view partly in section and showing method of uniting separate tubes into an integral structure.

In carrying out the method of tapering columns of uniform diameter a supporting structure is provided having a pair of parallel and laterally spaced sills or I-beams 9 mounted upon blocks

S, preferably of concrete, spaced longitudinally of the sills. A die carrier is suspended in interposed relation between the sills at a point intermediate the ends thereof by a supporting bracket 10 fixed upon and extending between the sills. 60 This die carrier (Figures 3 and 4) embodies a tubular head portion 11 with the outer contour of rectangular shape in cross section, and having pairs of parallel and laterally spaced ears 12 extended beyond one end and laterally of the tubular portion with one ear of each pair of ears arranged at a right angle to an ear of another pair of ears, as clearly shown in Figure 4.

The die comprises a series of members 13 of sector shape, shown in the present instance as 70 four in number, the curved side or end 14 of which sectors is arranged eccentric to the center of the axis of the sectors and having a groove 15 in the face thereof of arcuate shape in cross section and progressively narrowed or tapered from one end 75 15^a to the opposite end 15^b. These sectors are pivotally supported at the vertex between the pairs of ears 12 by pins 16 engaged in perforations 17 in the ears with the curved end 14 extending and adapted to have movement in the plane of the 80 axis of the die carrying head 11, the arcuate faces of the curved ends being disposed about the axis of the die carrying head to constitute segments of the die and the space between said faces the opening through the die. 85

By the arranging of the curved end 14 eccentric to the axis 16 of the sectors the space or opening between said faces will be of greater extent when the sectors are adjusted to the position shown in Figure 2 with the larger end of the arcuate recess 90 15^a in said faces opposed to each other, and as the sectors are moved or adjusted to position the smaller end of the arcuate recess 15^b in the faces in opposed relation to each other said space will be diminished, and the arcuate faces constituting a segment of a circle conforming to such diminished size. It will be obvious that by the gradual movement of the sectors that the space between the sectors will be gradually diminished and the arc of the segment will be correspondingly 95 diminished.

The sectors are simultaneously adjusted by racks 18, there being four in number equal to the number of the sectors, mounted to have longitudinal sliding movement in recesses 19 in the outer surface of the die carrying head 11 adjacent to the base of an ear of each pair of ears 12. These racks mesh with gears 20 mounted on the pins 16 concentric of the pivot support of the sectors and connected thereto whereby the gears 110

and sectors will have participating movement. The gears and sectors may be attached to each other and loosely mounted on the pins 16, or they may be fixed to the pins 16 and the latter rotatably mounted in the perforations 17 of ears 12. To adjust the racks and thereby the sectors through the gears simultaneously the racks are connected to an actuator in the form of a collar 21 shaped to conform to the exterior cross sectional shape 10 of the head carrying die 11 and slidably mounted thereon, the inner wall of the collar having recesses 21' therein for the engagement and securing of the racks 18 therein. It will be obvious that should the rack actuator 21 be adjusted on 15 the die carrying head to the right from the position shown in Figure 2 that the sectors will be adjusted in the direction of movement of the rack actuator, and that the curved ends 14 of the sectors will be moved in the plane and toward the 20 axis of the die carrying head, and when the rack actuator is adjusted in the opposite direction the sectors will be moved in the plane of and away from the axis of the die carrying head. To reduce a column such as a tube or circular stock A 25 to a smaller diameter the die sectors are adjusted to accommodate the size of the work. The work is drawn through or between the die sectors by engaging the end between the legs of a bifurcated portion 22 of a carriage C suspended between the 30 supporting sills upon which the carriage is mounted to travel along the same, the work being connected with the carriage by a pin 23 extended through perforations in the bifurcation legs and a hole formed in the work. The carriage is connected to power means (not shown) by a cable or 35 draw bar 24. As the work is drawn between the die members they are adjusted by the adjustment of the rack actuator on the die carrying head until the work assumes the desired cross sectional 40 shape.

In the method of forming a tubular column of the same diameter throughout to tapered and entasis form portions of the tube or column are first removed to provide tapered slots extended 45 through one end and toward the opposite end, as shown at 25 in Figure 9, the tube in the present instance being arranged with two of such slots arranged diametrically opposite, although it may be provided with a greater number of slots, which 50 may be desirable depending upon the diameter of the column or tube to be reduced. These slots are preferably formed by a milling cutter 44 of suitable structure, the cutting operation in forming the slots being commenced at one end and to one side of the longitudinal axis of the tube and the cutter being directed in an oblique direction 55 toward the axis and opposite end of the tube, the cutting operation being terminated as the cutter reaches the axis, whereupon the cutter is brought 60 back to the point of commencement when the operation is again performed on the opposite side of the longitudinal axis, as clearly shown in Figures 10 and 11. By so slotting the tube or column the portions *a* between the slots are of 65 progressively reduced width from the apices of the slots to the end. To shape the slotted column or tube to tapered entasis form the unslotted end portion 26 of the column is engaged between the die members and attached to the carriage as 70 hereinbefore described and as shown in Figure 2, when the column or work is drawn between the die members. To shape the slotted portion of the column to progressively reduced or tapered and entasis form means are provided operative 75 from the travel of the carriage along the support-

ing sills to adjust the die members proportionally to the travel or movement of the column to effect a decrease in the space between the die members. This is effected by adjusting the rack actuator 21 along a templet or bar 27 having a cam edge 27' conforming to the desired shape or entasis to which the column is to be shaped, said templet bar being supported to have longitudinal sliding movement and connected with the carriage C, as at 28, to participate in the movement of the column or tube A.

To operatively connect and adjust the rack actuator 21 from the templet bar a follower in the form of a flanged roller 29 engages and follows the cam edge of the templet, said roller being rotatably carried on a headed stud 30 secured in a carrier 31 pivotally supported at one end from an arm 32 mounted on a shaft 33 supported at the ends in bearings 34 fixed upon the supporting sills 9. The opposite end of the roller carrier 31 is pivotally connected to an arm 35 fixed on a shaft 36 rotatably supported at the ends in hangers 37 fixed to or forming a part of and extended downward from the bearings 34, said hangers being also supported intermediate the ends by the supporting sills by tie members 38 and spaced from the sills by spacers 39, the hanger at the right as viewed in Figure 1 also carrying a support 40 for the templet 27. The shaft 36 is in the nature of a rock shaft and is connected with the rack actuator 21 by a pair of arms 41 fixed on said shaft and extending upward therefrom and connected with the rack actuator by links 42 pivotally connected to opposite sides of the rack actuator, as at 43. The parts are shown at the commencement of 105 the operation of progressively narrowing the column or shaping it to tapered form in Figure 2, in which position the templet follower 29 is at the commencement of the cam edge 27' of the templet. As the column is drawn between the die 110 members and the follower rides upon the templet cam edge the follower carrier 31 will be raised or moved transversely to the longitudinal movement of the templet thereby rocking the shaft 36 and the arms 41 and through the link connection 42 of 115 the latter with the rack actuator 21 move said rack actuator to the right as viewed in Figure 2, and thus adjusting the die members to reduce the space between the faces of said die members, and effecting a shaping of the portions *a* of the column between the slots 25 to arcuate form in 120 cross section and the arc extending through substantially 180 degrees, and simultaneously therewith bringing the inner edges *b*, *c* of the walls of the slots into abutting relation, the slot walls 125 as the slots are cut being formed to incline toward the axis of the tube due to the form of the cutter, thereby not only gradually lengthwise diminishing the cross sectional area of the column but also maintaining it in circular shape and of 130 entasis form. After the column has been so shaped the abutting walls are welded together, as by electric welding, as shown at *d* in Figure 12, by flowing the welding material into the recess formed by the inclined slot walls, which may be 135 done simultaneously with the forming of the column as it is drawn between the die sectors.

The tubing which is reduced in cross section and progressively narrowed from one end to the opposite end is of stock size and should the length 140 of the desired flag pole, mast, boom or spar come within such stock length only one section of the tube length is required. However, should the length of the flag pole, mast, boom or spar be required to be of a length greater than a stock size 145

then successive sections of tubing of stock size are reduced in cross section and the sections united in endwise relation, the successive sections being progressively narrowed to smaller size and united 5 with the end of larger cross section of one section in alined relation to the smaller end of the adjacent section by a tubular coupling member in the form of a sleeve 45 having the opposite ends engaged in the mating ends of the successive sections with an intermediate portion exposed and 10 annularly reduced in circumference when the successive sections of tubing and the sleeve are united together by welding, by flowing the welding material into the annularly reduced portion 15 of the sleeve and between the ends of the tube sections flush with the outer surface thereof and thus also maintain the straight line effect of the pole, as shown at 46 in Figure 13.

If desired the stock to start from may comprise 20 two sections of like arcuate shape in cross section with the arc at one end extending through 180 degrees so that the longitudinal edges of one section at one end may be brought into abutting relation with the longitudinal edges at one end of the other section, as shown for illustrative purposes by dot and dash lines 47 in Figure 9, and 25 form a tubular portion at one end, which end constitutes the starting end in the method of reducing the plates so formed to tubular shape and 30 progressively narrowed from one end to the op-

posite end, said ends with the longitudinal edges of one plate in abutting relation to the longitudinal edges of the other plate, as indicated by dot and dash line 47, being positioned between the faces 14 of the die sectors 13 preparatory to the drawing of the tube sections through the die in the reducing of the same.

While I have illustrated and described one embodiment of apparatus for carrying out the method it will be obvious that various modifications may be made in construction and arrangement of parts without departing from the scope of the invention, and that portions may be used with others and come within the scope of the invention.

Having thus described my invention I claim:

The method of making tapered columns from tubes having the same diameter for the entire length thereof, consisting in removing diametrically opposite portions of V shape from the tube and extending through one end toward the opposite end of the tube, and then bringing the inner edges of the opposite wall portions of the slots progressively into abutting relation and simultaneously shaping the portions of the tube between the slots to circular form in cross section and of progressively tapered and entasic form to the first mentioned end.
